ELECTRIC WEFT DETECTING SYSTEM
FOR LOOMSVictor F. Sepavich, Worcester, Mass., assignor to
Crompton & Knowles Loom Works, Worcester,
Mass., a corporation of Massachusetts

Application March 11, 1947, Serial No. 733,885

7 Claims. (Cl. 139—273)

1

This invention relates to improvements in electric weft detecting systems for looms and it is the general object of the invention to provide such a system wherein indication of weft exhaustion may be retained any desired length of time to be utilized at some point in the cycle of the loom subsequent to the time of indication.

In certain types of weft replenishing looms the weft detector indicates weft exhaustion an appreciable interval of time before the indication can be utilized to initiate a replenishing operation. This condition exists for instance in pick and pick weft replenishing looms wherein the weft detector is at one side of the loom and the reserve bobbin magazine or replenishing mechanism is at the opposite side. In such looms the detector indicates exhaustion of a particular shuttle four picks or so before that shuttle is in position for replenishment at the opposite side of the loom. It is an important object of the present invention to hold an indication by means of an electronic circuit which maintains a solenoid or the like energized until the point in the loom cycle is reached at which such energization can be utilized for setting the magazine for transfer.

The electronic tube is energized preferably by a unidirectional current and will continue to energize the solenoid until the plate of the tube either becomes negative or has its potential reduced to zero. This result can be accomplished by either of two means set forth hereinafter. In one of these means the lifting of the transferer latch to transfer position causes opening of a switch which breaks the plate circuit, while in the other means the periodic shifting of the bobbin stack selector of the magazine opens the plate circuit.

With these and other objects in view which will appear as the description proceeds, my invention resides in the combination and arrangement of parts hereinafter described and set forth.

In the accompanying drawings, wherein two forms of the invention are set forth,

Fig. 1 is a front elevation of part of an automatic pick and pick weft replenishing loom having the first form of the invention applied thereto.

Fig. 2 is an enlarged detailed side elevation looking in the direction of arrow 2, Fig. 1, showing the plate controlling circuit switch closed in full line position and open in dotted line position.

Fig. 3 is a detailed horizontal section on line 3—3 of Fig. 2.

Fig. 4 is a side view of the reserve bobbin maga-

zine as seen from the center of the loom having the modified form of the invention applied thereto.

Fig. 5 is an enlarged rear detailed elevation, partly in section, looking in the direction of arrow 5, Fig. 4; and

Fig. 6 is a diagrammatic view of the electric circuit used with the invention.

Referring particularly to Fig. 1, the loom frame 10 has mounted thereon a lay 11 having right and left gangs of shifting shuttle boxes RG and LG, respectively. These boxes shift vertically by means of box operating mechanisms not shown but operating through box lifter rods 12 and 13. 15 The gang RG will be in the down position shown at the right of Fig. 1 for the first two picks of a four-pick cycle and then will be up for the next two picks, thus completing a four-pick cycle. The gang RG then falls to the low position to start another four-pick cycle. The gang LG is also operated on a four-pick cycle, but it shifts on those beats of the loom when the gang RG is stationary with respect to the lay. In this way one or the other of the gangs RG and LG shift 20 each pick of the loom, but each gang is up for two picks and then down for two picks. The loom operates with three shuttles S', S2 and S3 which preferably have diverse wefts. These shuttles are picked one after the other, each shuttle after being active for one pick remaining idle for two picks.

A weft detecting mechanism D is in the present instance mounted on the lay over the gang LG to detect the condition of weft in the top shuttle box 15 when gang LG rises to its high position. The detector D includes a detector finger 16, an electric switch 17 which is normally open and remains open when the detector finger engages an ample weft supply in box 15. When 35 the supply is depleted however the detector finger slides laterally in known manner to close the switch 17.

On indicating beats of the loom switch 17 will be closed by the depleted shuttle in box 15 upon 40 completion of upward movement of gang LG and will remain closed until this gang descends to low position. When gang LG descends the switch 17 will open, but at this time the depleted shuttle is still on the left end of the loom and must be 45 picked to the right end as viewed in Fig. 1 into box 18 and the latter then raised before replenishment can occur.

The magazine M for the reserve bobbins is supported in known manner on the frame of the 50 loom and includes four vertically slidable bobbins

releasers 20, 21, 22 and 23, see Fig. 4. These releasers are normally down but can be raised and then lowered by a selector mechanism designated generally at 25.

The selector includes a rod 26 mounted for horizontal slidable movement on the magazine and carrying spaced fingers 27 and 28 which register with one releaser at a time as the selector moves longitudinally from the front position shown in Fig. 4 to rear position. In any one of the four positions which the selector can occupy it will register with and be able to actuate one of the releasers.

The selector is controlled by a lever 30, see Fig. 3, pivoted on the upper end of a block 31 which reciprocates vertically in a guide 32. One end of lever 30 is operatively connected by rod 33 to the selector, while the other end of lever 30 is free but prevented from rising above its normal position by a pin 35 held in fixed position thereover on a stand 36. A controller or pin 38 is provided to move under the free end of lever 30 whenever a replenishing operation is to be initiated. Ordinarily pin 38 is out of the path of lever 30.

A cam 40 on the bottom shaft 41 of the loom rotates every second pick of the loom and causes rising and falling of a rod 42 the upper end of which is connected to the reciprocating block 31. Cam 40 causes lever 30 first to move upwardly from its normal position, then return to normal position, then descend from its normal position, and then return to normal position. These movements of lever 30 occur in a two-pick cycle as is usual in multicolor weft replenishing looms and cause rocking of the selector 25 in a clockwise direction as viewed in Fig. 1 every second pick of the loom due to engagement of lever 30 with the stationary pin 35. If controller pin 38 is under lever 30 when lever 42 descends the latter will depress rod 33 to cause rocking of the selector to raise one of the releasers. If pin 38 is not under lever 30 the latter has an idle loom motion.

The invention has been applied to a multicolor pick and pick weft replenishing loom wherein each shuttle carries weft different from the wefts of the other two shuttles. The magazine will have a stack of reserve bobbins for each type of weft, and it will be understood that when the invention is used with a loom of this type only three stacks and releasers will be in use, one of them remaining idle since there is no fourth shuttle corresponding to it. In the present description it is assumed that the first three releasers 20, 21 and 22 will be active in rotation and releaser 23 will be idle.

Longitudinal movement of selector 25 is effected by means of a lever 45 connected as at 46 to the rod 26. Lever 45 is acted upon by spring 47 which tends to move the color selector to its front position, or to the right hand position as shown in Fig. 4. A control rod 48 acting in opposition to spring 47 causes counterclockwise movement of lever 45 as viewed in Fig. 4 to move the color selector rearwardly, or to the left. By known means not set forth herein the rod 48 is so controlled that it causes the selector to register with releaser 20 for the first four picks of a twelve-pick sequence, then register with releaser 21 for the next four picks, and then register with releaser 22 for the remaining four picks. The selector then moves forwardly to register with releaser 20 to start another sequence of movements. In this way the selector 25 has regular movements at

four-pick intervals regardless of replenishing operations.

In the operation of the mechanism thus far described, lever 30 will rise and fall as already described and the boxes will shift to move the shuttles one at a time and at four-pick intervals into detecting relation with respect to the weft detector D. If no indication of weft exhaustion is given pin 38 is out of the path of lever 30 and the latter has idle movements. All of the releasers 20, 21 and 22 remain down and no bobbin is in transfer position in the magazine. If, however, the controller pin should be in the path of lever 30 its normal downward movement is interrupted and the selector is given a counterclockwise rotation as viewed in Fig. 1 to lift one or another of the releasers 20-22, and shortly thereafter has its regularly recurring clockwise movement to depress the previously raised releaser to advance a bobbin to transfer position. These operations occur at an interval of time after indication of exhaustion is given by the detector D and do not ordinarily start until after the switch 17 has been opened by descent of the depleted weft supply in shuttle box 15. It is this condition which necessitates holding pin 38 in indicating position until down motion of lever 30 can be utilized to initiate bobbin release and raise latch 49 of the transerrer arm 50 into the path of lay carried bunter 51 to set the magazine for transfer.

In carrying my present invention into effect I utilize an electronic circuit including a gas filled power tube which will be fired immediately upon indication of exhaustion of the detector due to closure of a switch 17 and will remain firing until its output or plate circuit is interrupted.

The circuits are shown in Fig. 6 and may be substantially the same for either form of the invention. The circuit includes power wires 55 and 56 preferably supplying alternating current at some commercial voltage, such for instance as 110 volts. A transformer T has a primary 57 connected across wires 55 and 56 and has a secondary 58 wound to supply alternating current of relatively low voltage. A gas filled electronic power tube E has a plate 60, control and shield grids 61 and 62, respectively, a cathode 63, and a heater filament 64 therefor.

50 The filament is energized by the following filament circuit: secondary 58, wire 65, resistance 66 if desired, filament 64, wire 67 and wire 68 back to the secondary. This circuit will supply a relatively heavy current at low voltage as is customary for the filaments of electronic tubes having indirectly heated cathodes.

The secondary 58 also supplies potentials for the detecting circuit which in the present instance is operated preferably by direct or unidirectional current. A full wave rectifier 70 has its positive side grounded by wire 71 and is energized by the secondary 58 by means of part of the circuit already traced and wires 72 and 73. The negative side of the rectifier is connected by wire 75 to a resistance 76 which in turn is connected by wires 77 and 78 to one side of switch 17 the other side of which is grounded as at 79. The control grid 61 is connected to wire 77 by wire 80 and is normally negative with respect to the cathode 63 which is grounded by wire 81.

So long as switch 17 is open the detecting circuit is dead and the control grid 61 is maintained negative with respect to the cathode and prevents firing of tube E. Whenever switch 17 is

closed, however, the potential of the control grid rises to the level of ground and the tube fires.

In order to maintain the tube E in firing condition it is energized by unidirectional current derived from a second full wave rectifier 85 connected by wires 86 and 87 to the power wires 55 and 56, respectively. The negative side of rectifier 85 is grounded as at 88, while its positive side is connected by wire 89 to a switch which in Fig. 6 is designated at 90, but which in fact will be either of two switches to be set forth hereinafter, one for each form of the invention. Wire 91 leads from switch 90 to a solenoid S which in turn is connected by wire 92 to plate 60. The rectifier 85 will ordinarily supply a higher voltage than does rectifier 70, and it tries continuously to cause firing of the tube so long as switch 90 is closed, but is prevented from doing so by the normal negative condition of grid 61. When the tube is able to fire, however, the following plate-solenoid circuit will be closed: rectifier 85, wire 89, closed switch 90, wire 91, solenoid S, wire 92, plate 60 through the tube E to cathode 63, wire 81 to ground, and wire 88 back to the rectifier. Since rectifier 85 supplies a unidirectional current the tube E will continue to fire so long as switch 90 is closed and effect continued energization of solenoid S. Opening of switch 90 will interrupt the plate circuit and deenergize the solenoid.

In the preferred form of the invention the plate circuit interrupting switch 90 is controlled by transerrer latch 49. Ordinarily the latch hangs down in the idle position shown in Fig. 2, and a stud 95 thereon engages arm 96 of switch 90 to hold the latter closed. The full line position of arm 96 in Fig. 2 corresponds to the full line position of switch 90 in Fig. 6. When the selector 25 rocks first in one direction and then in the opposite direction as already described it causes latch 49 to move from the full line to the dotted line position in Fig. 2 in well-known manner not specifically described herein. Stud 95 thereupon moves away from arm 96 and switch 90 automatically opens, the dotted lined position of arm 96 in Fig. 2 corresponding to the dotted line position of switch 90 in Fig. 6.

In this preferred form of the invention it will be understood that inasmuch as the latch 49 is normally down the rectifier 85 will be electrically connected to the solenoid and plate 60 of the tube E, and as soon as the tube fires it will continue to fire until the latch 49 is lifted to transfer position.

The solenoid S is mounted on the stand 36 and has a core 100 connected to the previously mentioned control pin 38. When the solenoid is deenergized spring 101 holds the controller pin 38 to the left out of the path of lever 30, see Fig. 3, but when the solenoid is energized its core moves to the right and moves the controller pin under lever 30, or at least will tend to move the control pin under the lever 30, and will do so when the latter is in its neutral position.

The cam 40 is so timed that it will start a downward movement of lever 30 just before switch 47 can be closed by rising of gang LG in the event that the weft supply in box 15 is depleted. As a result of this timing the greater part of the two picks of the first cycle of lever 30 will be idle, and the controller pin 38 will not become effective to interrupt the normal down idle motion of lever 30 until the beginning of the next two-pick cycle of the lever. In this way a delay is attained between indication of weft exhaustion in box 15 when the latter is up and setting of the latch 49

for transfer. There is ordinarily an interval of time between the disengagement of detector finger 16 from the weft supply in box 15 as the latter descends and downward movement of lever 30 in the second of the aforesaid pairs of two-pick cycles. It is for the purpose of keeping the solenoid energized during this gap or short interval that I use direct current for energization of the tube E to hold pin 38 under lever 30. The tube is therefore able to keep the solenoid energized even though contact is broken at switch 17.

In the second form of the invention I make use of the periodic longitudinal movements of selector 25. The rod 26 is extended to the rear, or to the left as viewed in Fig. 4, and has three trip bosses 105, 106 and 107 corresponding respectively to releasers 20, 21 and 22. These bosses control a switch 110 by engagement of its arm 111 which is normally pressed against the rod 26 out of engagement with the bosses when switch 110 is closed. When rod 26 moves endwise as described one or another of the bosses raises arm 111 to open switch 110 and interrupt the plate-solenoid circuit. Since the selector 25 moves longitudinally at regular four-pick intervals it can be relied upon to break this circuit after the time has passed in each four-pick cycle when downward movement of lever 30 could be interrupted by control pin 38 in the event of indication of weft exhaustion. I prefer to shift the selector during the latter part of the last pick of the four pick sequence after lever 30 returns to neutral position following its last up motion of the sequence.

From the foregoing it will be seen that I have provided simple means for maintaining the solenoid S energized subsequent to opening of switch 17 after the detector D has given indication during the indicating interval, this result being accomplished by an electronic tube supplied preferably from a source of direct or unidirectional current. In the preferred form of the invention the plate circuit which includes the solenoid will remain energized until latch 49 rises during the fourth pick of the four pick sequence to open switch 90 incident to setting of the magazine for transfer. In the modified form of the invention the plate circuit is opened periodically due to shifting of the selector 25, preferably during the last pick of the four pick sequence. In both forms of the invention the plate circuit will be interrupted near the end of the sequence with consequent deenergization of solenoid S and restoration of the detecting system to normal condition before the detector D has an opportunity to initiate another replenishing operation in the following sequence.

Having thus described my invention it will be seen that changes and modifications may be made therein by those skilled in the art without departing from the spirit and scope of the invention and I do not wish to be limited to the details herein disclosed, but what I claim is:

1. In a weft replenishing pick and pick loom 65 operating with shuttle boxes at each end thereof and having a weft detector on one side thereof and a reserve bobbin magazine on the opposite side thereof, the loom having a shuttle which moves to inactive detecting position in the boxes 70 on said one side of the loom to give indication of weft exhaustion by an electric weft detector at the beginning of a four-pick sequence and then moves away from the detector during the second pick of the sequence, an actuator moving first in 75 one direction during the third pick of the se-

quence after the shuttle moves away from the detector and thereafter during the fourth pick of the sequence moving in the opposite direction, a controller for the actuator normally in non-controlling position relatively thereto, a solenoid which when energized causes the controller to be in controlling position relatively to the actuator, a bobbin releaser for the magazine operated by the actuator to release a bobbin for transfer if the controller is in controlling position relatively to the actuator when the latter moves in said one direction, normally deenergized electric circuit means including the solenoid and an electronic tube, means causing said circuit to be energized to energize the solenoid when the detector indicates weft exhaustion, said circuit means remaining energized due to the electronic tube after the shuttle moves away from the detector, and means effective after the actuator moves in said one direction to open said circuit means.

2. In a weft replenishing loom effective to give indication of weft exhaustion during a given interval of the loom cycle, bobbin release means, an actuator for said release means moving subsequent to said interval, a controller for said actuator normally out of controlling relation with respect to the actuator but when in controlling relation with respect thereto causing said actuator to effect operation of the bobbin release means, a solenoid for the controller effective when energized to move the controller into controlling relation with respect to the actuator, a normally dead electric circuit for the solenoid including an electronic tube, electric control means for the electronic tube effective when the detector indicates weft exhaustion to energize said circuit, said circuit thereafter due to said electronic tube continuing energization of said circuit and solenoid after said interval, and electric means effective subsequent to operation of the release means by the actuator to open said circuit.

3. In a weft replenishing loom having an electric weft detector which gives indication of weft exhaustion during a given interval of the cycle of the loom, an actuator having operative movements subsequent to said interval, transfer mechanism including a latch normally in idle position, a controller for the actuator normally idle relatively to the latter, means effective if the controller is in operative relation with respect to the actuator when the latter has said movements to cause movement of said latch to transfer position, a normally deenergized electric circuit including an electronic tube and a solenoid which when energized effects movement of the controller into operative relation with respect to the actuator, electric means effective when the detector indicates weft exhaustion to energize said circuit and the solenoid, said circuit due to said electronic tube remaining energized subsequent to said interval, and electric means controlled by the latch and effective when the latter moves to transfer position to open said circuit.

4. In a weft replenishing loom having a plurality of bobbin releasers and a selector moving to register with the releasers one at a time, an electric weft detector giving an indication of weft exhaustion during a given interval in the cycle of loom operation, an actuator moving subsequent to said interval, a controller normally idle with respect to the actuator but effective when in operative relation with respect to the actuator to cause the selector to operate the bobbin releaser registered therewith, normally deenergized electric circuit means including an electronic

tube and a solenoid which when energized causes the solenoid to move the controller into operative relation with respect to the actuator, electric means controlling the tube and effective upon indication of weft exhaustion by the detector to cause energization of said circuit by current flowing through the tube, said circuit due to the tube continuing energization of the solenoid subsequent to said interval and until the actuator moves, and electric means effective subsequent to movement of the actuator to open said circuit means.

5. In a weft replenishing loom having a plurality of bobbin releasers and a selector moving to register with the releasers one at a time, an electric weft detector giving an indication of weft exhaustion during a given interval in the sequence of loom operation, an actuator moving subsequent to said interval, a controller normally idle with respect to the actuator but effective when in operative relation with respect to the actuator to cause the selector to operate the bobbin releaser registered therewith, electric circuit means including an electronic tube and a solenoid which when energized causes the solenoid to move the controller into operative relation with respect to the actuator, said circuit being normally dead but effective upon indication of weft exhaustion by the detector to energize the solenoid by current flowing through the tube and said circuit due to tube continuing energization of the solenoid subsequent to said interval and until the actuator moves, and electric means operated by movement of the selector to open said circuit.

35. 6. In a weft replenishing loom having a part to be moved preparatory to a replenishing operation of the loom, an electric weft detector indicating weft exhaustion during a given interval in the cycle of the loom, an actuator for said part moving subsequent to said interval, a controller normally idle relatively to the actuator but effective when in operative relation with respect to the actuator to cause the latter to move said part, a solenoid for said controller which when energized moves the latter into operative relation with respect to the actuator, a gas filled electronic power tube having a grid normally effective to prevent flow of current through the tube, electric circuit means including said tube and solenoid and including a source of unidirectional current effective to energize the solenoid by electric current flowing through the tube whenever current can flow through the tube, electric means effective upon indication of weft exhaustion by the detector to alter said grid in such a manner as to permit current to flow through the tube during said interval, said tube and source effective subsequent to said interval to continue energization of the solenoid until the actuator moves, and electric means effective subsequent to operation of said part by said actuator to open said circuit means.

7. In a weft replenishing loom having a part to be moved preparatory to a replenishing operation of the loom, an electric weft detector indicating weft exhaustion during a given interval in the cycle of the loom, an actuator for said part moving subsequent to said interval, a controller normally idle relatively to the actuator but effective when in operative relation with respect to the actuator to cause the latter to move said part, a solenoid for said controller which when energized moves the latter into operative relation with respect to the actuator, a gas filled electronic power tube having a grid normally ef-

fective to prevent flow of current through the tube, electric circuit means including said tube and solenoid and including a source of unidirectional current effective to energize the solenoid whenever current can flow through the tube, electric means effective due to indication of wett exhaustion by the detector to alter said grid in such a manner as to permit current to flow through the tube during said interval, said tube and source effective subsequent to said interval to continue energization of the solenoid until the actuator moves, and means controlling said circuit means and effective incident to movement

of said part by said actuator to open said circuit means.
